ROCK DRILL

Filed Jan. 7, 1928

Fig. 1.

UNITED STATES PATENT OFFICE

MERVIN C. HUFFMAN, OF CLAREMONT, NEW HAMPSHIRE, ASSIGNOR TO SULLIVAN MACHINERY COMPANY, A CORPORATION OF MASSACHUSETTS

ROCK DRILL

Application filed January 7, 1928. Serial No. 245,174.

This invention relates to rock drills, and more particularly to a hole blowing device for fluid actuated rock drills of the hammer type.

An object of this invention is to provide an improved hole blowing device for a rock drill. Another object is to provide an improved hole blowing device for fluid actuated rock drills of the hammer type whereby the fluid distribution valve may be held immovable to effect a hole blowing operation. Still another object of this invention is to provide an improved hole blowing device for a rock drill whereby the fluid distribution valve may be pneumatically shifted and held immovable to effect a hole blowing operation. Still another object of this invention is to provide an improved hole blowing device for a rock drill, the device including a combined buffer plug and piston member actuated by pressure fluid for pneumatically shifting and holding the valve immovable to effect a hole blowing operation. Yet another object is to provide an improved hole blowing device wherein a combined buffer plug and piston member is provided for shifting and holding the fluid distribution valve immovable to effect a hole blowing operation, and valve controlled means for controlling movement of the combined buffer plug and piston member. These and other objects of this invention will however subsequently more fully appear as the description proceeds.

In the accompanying drawings, there is shown for purposes of illustration one form which the invention may assume in practice.

In these drawings,—

Fig. 1 is a central longitudinally extending, vertical sectional view through a rock drill with which the improved hole blowing device is incorporated, the parts being shown in position to effect a hole blowing operation.

Fig. 2 is a view similar to Fig. 1 with the parts shown in a different position.

Fig. 3 is a fragmentary transverse sectional view taken substantially on line 3—3 of Fig. 1.

Fig. 4 is a side elevational view of the automatic fluid distributing valve.

In the illustrative embodiment of the in-

vention there is shown a rock drill of the pressure fluid actuated percussive type comprising a cylinder 1 having a bore 2 in which a hammer piston 3 is mounted for reciprocal movement. The hammer piston 3 is provided with a forwardly projecting striking bar 4 reciprocably mounted within a bore 5 formed within a usual front cylinder head or buffer ring 6. The striking bar 4 is adapted to impart a series of blows on the shank of a hollow drill steel 7 loosely mounted in a usual manner within a chuck bushing 8 secured to a chuck sleeve 9 rotatably mounted within a usual chuck housing 10. As illustrated, the rear end of the cylinder bore 2 is closed by a suitable washer 11 while interposed between this washer and a rear head member 12 is a usual ratchet ring 13. As is usual in rock drills of the type disclosed, the chuck housing 10, the front cylinder head 6, cylinder 1, rear washer 11, and rear head 12, and the ratchet ring 13 are maintained in assembled relation by side rods or bolts (not shown).

Drill steel rotation mechanism operated by the hammer piston 3 is provided and this rotation mechanism comprises a spirally grooved rifle bar 14 extending forwardly through the washer 11 into engagement with the hammer piston 3 in the usual manner. During the forward stroke of the hammer piston, the rifle bar freely rotates, thereby permitting free movement of the hammer piston during the working stroke. Upon the return stroke of the piston the rifle bar is held stationary by the usual ratchet and pawl mechanism generally designated 15, and as a result the piston is slightly rotated. Rotary movement of the piston 3 is transmitted to the drill steel 7 by means of straight flutes 16 formed on the periphery of the striking bar 4. The flutes 16 engage straight lugs 17 formed on a usual chuck nut 18 threadedly connected to the rotatable chuck sleeve 9. From the foregoing it is evident that the drill steel 7 is intermittently rotated during reciprocation of the hammer piston.

Projecting laterally from the cylinder 1 is a valve chest 19 having a bore 20. Suitably positioned within the bore 20 are oppo-

sitely positioned valve sleeves 21 and 22, each having bores 23 and 24 of different diameter. Reciprocably mounted within the bores 23, 24 is an automatic fluid distributing valve 25. This fluid distributing valve may be of any suitable type as the invention is not dependent upon the particular valve illustrated for its successful functioning and the invention may be used in connection with any type of valve which controls both the admission of pressure fluid to the cylinder and exhaust of pressure fluid therefrom. The valve 25 in this instance is of the well-known three-spool differential type having an enlarged central spool 26 and end spools 27, the spools 26, 27 having a sliding fit with the bores 24, 23 respectively. Herein the central spool 26 of the valve controls the admission of pressure fluid through an inlet 28 to the bore 24 and the end spools 27 control free exhaust ports 29 and 30 respectively leading from the bores 23 to atmosphere. The end spools 27 have opposed actuating faces against which pressure fluid may act for effecting movement of the distribution valve from one extreme position to the other. Movement of the valve 25 in one direction is limited by a buffer plug 31 rigidly secured to the valve sleeve 21 while movement of the valve in the opposite direction is limited by a buffer plug 32 carried within the valve sleeve 22 and which herein constitutes a part of the improved hole blowing device as will later be described. Pressure fluid admitted into the bore 24 of the valve chamber may pass to the rearward and front ends of the cylinder bore 2 to effect reciprocation of the hammer piston 3 through usual supply passages 33 and 34 respectively. In this instance the supply passages 33, 34 also serve as exhaust passages for exhausting the pressure fluid from the cylinder.

As is usual in rock drills employing the type of valve herein disclosed, piston controlled throwing passages are provided for admitting pressure fluid from the cylinder to act against the opposed actuating faces at the ends of the valve. Such throwing passages may be crossed as in the present instance in which a throwing passage 35 leads from the front end of the cylinder bore to the bore 23 at the rearward end of the valve 25 and is controlled by the hammer piston 3. A second piston controlled throwing passage 36 leads from the rearward end of the cylinder bore 2 to the bore 23 at the forward end of the valve 25.

The improved hole blowing device also includes a reciprocable plunger valve 37 slidably mounted in a bore 38 formed within the valve sleeve 22, this plunger valve being provided with a push button or other suitable operating element 39, and being grooved at 40 intermediate its ends. As illustrated, the plunger valve 37 is normally maintained in its inoperative position by means of a coiled

spring 41 interposed between the bottom of the bore 38 and the lower end of the valve, movement of the plunger valve within the bore being limited by a pin and slot connection 42. The bore at the lower end of the valve 37 is vented to atmosphere through a restricted port 43. In accordance with this illustrative embodiment of the invention, the valve sleeve 22 has formed therein in axial alignment with the valve 25 a bore 44 within which the improved buffer plug 32 is reciprocably mounted, the member 32 being in the form of a combined buffer plug and piston member. Pressure fluid is adapted to be admitted to the bore 44 at the forward side of the member 32 through a passage 45 (see Fig. 3) connecting the pressure fluid inlet 28 with the bore 38 and the port 46 connecting the bore 38 with the bore 44. As shown, the bore 38 is connected to atmosphere through a vent 85 passage 47.

In the normal operation of the rock drill, when the distribution valve 25 is in the position shown in Fig. 2, pressure fluid flows through inlet passage 28 past the rear surface of the central spool 26 and through the passage 33 to the rear end of the cylinder bore 2 where it acts on the rear surface of the piston 3 and moves the latter forwardly to strike an unimpeded blow on the drill steel 95 7. The exhaust fluid from the forward end of the cylinder bore flows through the passage 34 past the rear surface of the front end spool 27 of the distribution valve and through the exhaust passage 30 to atmosphere. The distribution valve is held in its forward position by reason of the larger effective area of the central spool and by the pressure acting on the rear end spool. When the hammer piston uncovers the throwing passage 36, pressure fluid is admitted from the rear end of the cylinder bore to the forward end of the valve 25 and consequently the latter is thrown rearwardly to the position shown in Fig. 1. Pressure fluid now enters the forward end of the cylinder bore through inlet passage 28 past the forward surface of the central spool 26 on the valve and through the passage 34 and consequently the hammer piston is moved rearwardly. Exhaust now takes place through passage 33 past the forward surface of the rear spool 27 of the distribution valve and through the exhaust passage 29 to atmosphere. As soon as the piston 3 has uncovered the throwing passage 35, the distribution valve 25 is again shifted to its forward position and this cycle of events continues during the normal operation of the drill.

When it is desired to effect a hole blowing operation, the operator presses his thumb or finger against the push button 39 and depresses the plunger valve 37, moving the latter from the position shown in Fig. 2 to the position shown in Fig. 1. When the plunger 100

valve 37 is in the position shown in Fig. 1, the groove 40 connects the passage 45 with the port 46 and consequently pressure fluid is admitted from the inlet 28 to the bore 44 at the forward end of the piston member 32. As a result, the member 32 is moved rearwardly under the action of the pressure fluid, thereby shifting the valve 25 against the opposing pressure acting on the rear pressure area of the valve to the position shown in Fig. 1 and holding the same immovable against the rear buffer plug 31. Pressure fluid is then admitted from the inlet 28 past the forward surface of the central spool 26 of the distribution valve and through the passage 34 to the forward end of the cylinder bore 2. The continuous supply of pressure fluid flowing to this end of the cylinder bore forces the hammer piston 3 rearwardly against the rear cylinder washer 11 and consequently the pressure flows from the cylinder bore through the flutes 16 on the striking bar 4, through the chuck nut 18 and thence through the bore in the drill steel 7 to the bottom of the drill hole. Upon release of the push button 39, the plunger valve 37 is automatically returned to its inoperative position by the spring 41 as shown in Fig. 2, thereby cutting off communication between, the passage 45 and the port 46 and connecting the latter with the port 47 and as a result the bore 44 at the forward end of the member 32 is vented to atmosphere. The pressure fluid flowing from the cylinder bore through throwing passage 36 maintains the piston member 32 in its extreme rearward position as shown in Fig. 2 where it will then act as a valve buffer. The distribution valve 25 will then resume its normal operation and the drill will again function in a normal manner. These and other uses and advantages of this invention will be clearly apparent to those skilled in this art.

While I have in this application specifically described one form which this invention may assume in practice, it will be understood that this form of the same is shown for purposes of illustration and that the invention may be modified and embodied in various other forms without departing from its spirit or the scope of the appended claims.

What I claim as new and desire to secure by Letters Patent is:

1. In a fluid actuated rock drill of the hammer type, the combination of a cylinder having a bore and a piston reciprocable therein, means operative in a predetermined relative position of said piston with respect to said cylinder to conduct fluid to a hollow drill steel to blow the hole, a valve chest having a chamber and a fluid distributing valve in said chamber controlling both the supply and exhaust for said cylinder, valve throwing passages between the opposed spaces in the valve chest chamber at the ends of the

distributing valve and the cylinder bore for supplying pressure fluid for actuating said valve, and a hole blowing device including a fluid actuated plunger projecting in the valve chest chamber at one end of said valve and normally constituting a stop for the valve, said plunger also forming an end wall for the valve chest chamber and means under operator control for supplying fluid to actuate said plunger, said plunger being movable to effect shifting of the fluid distributing valve against the resisting throwing pressure and for holding said distributing valve immovable in a position to maintain the piston in a position to effect a hole blowing operation.

2. In a fluid actuated rock drill of the hammer type, the combination of a cylinder having a bore and a piston reciprocable therein, means operative in a predetermined relative position of said piston with respect to said cylinder to conduct fluid to a hollow drill steel to blow the hole, a valve chest and a fluid distributing valve therein controlling both the supply and exhaust of pressure fluid for said cylinder, buffer plugs for limiting movement of said valve in opposite directions, one of said buffer plugs being mounted for reciprocable movement in said valve chest, valve throwing passage between opposed spaces in the valve chest at the ends of said distributing valve and the cylinder bore for supplying pressure fluid for actuating said valve, and a hole blowing device comprising means for admitting pressure fluid to act on one end of said reciprocable buffer plug for effecting movement of the latter to shift the distributing valve against the resisting throwing pressure and for holding said distributing valve immovable against the other buffer plug to effect a hole blowing operation.

3. In a fluid actuated drill of the hammer type, the combination of a cylinder, a hammer piston, means operative in a predetermined relative position of said cylinder and piston to conduct cleansing fluid to a hollow steel to blow a hole, fluid supply and exhaust means for said cylinder including a distributing valve operative in a predetermined position thereof to bring said piston to the predetermined relative position for hole blowing and there to maintain it, and means for bringing said distributing valve to such position and holding it there including a fluid actuated element normally constituting a buffer to limit valve movement but movable under fluid pressure to move and hold the distributing valve and operator controlled valve means controlling fluid supply relative to said fluid actuated element.

In testimony whereof I affix my signature.

MERVIN C. HUFFMAN.
